(57) **CLAIM**

The ornamental design for an automobile tag, as shown and
described.

DESCRIPTION

FIG. 1 is a front perspective view of an automobile tag shown
on an automobile. Broken lines are for illustrated purposes
only and form no part of the claimed design.

FIG. 2 is a front plan view of the automobile tag of FIG. 1.

FIG. 3 is a rear plan view of the automobile tag of FIG. 1.

FIG. 4 is a top plan view of the automobile tag of FIG. 1. The

bottom plan view is identical to the top plan view; and,

FIG. 5 is a right side plan view of the automobile tag of FIG.

1. The left side plan view is identical to the right side plan

view.
